UNITED STATES PATENT OFFICE.

JAMES DE B. WALBACH, OF GALVESTON, TEXAS.

POCKET HAIR-BRUSH.

1,282,996.

Specification of Letters Patent.

Patented Oct. 29, 1918.

Application filed July 30, 1917. Serial No. 183,556.

To all whom it may concern:

Be it known that I, JAMES DE B. WALBACH, a citizen of the United States, residing at Galveston, in the county of Galveston and State of Texas, have invented certain useful Improvements in Pocket Hair-Brushes, of which the following is a specification, reference being had therein to the accompanying drawing.

10 This invention has reference generally to that class of inventions known as brushing and scrubbing and more particularly relates to a pocket military hair brush.

As the primary aim and object this invention 15 consists in the provision of a novel brush movably mounted in a supporting frame with which coöperates improved actuating means for placing the bristle holders in an extended or operative position or for 20 moving the bristle holders into a folded inactive position.

It is an equally important object of this invention to provide improved means for inclosing the supporting frame subsequent to 25 the placing of the brush in a folded position so that the entire device may be readily placed in a compact form and conveniently carried in the pocket of the user.

More particularly the present invention 30 embraces the provision of coöperative means on the actuating means and on the supporting frame for facilitating the maintenance of the bristle holders in either a folded or extended position.

35 It is a more specific object of this invention to provide a flexible cover on the casing with improved means for retaining a comb and mirror or other toilet articles; and to also provide improved means for operably 40 connecting the actuating means to the bristle holders.

Among the other aims and objects of this invention may be recited the provision of a device of the character mentioned with a 45 view to compactness, in which the number of parts are few, the construction simple, the cost of production low and the efficiency high.

Other improvements and novel details in 50 the construction and arrangement of the various parts of the apparatus will be brought out more in detail in the description to follow which for a clear understanding of the invention should be considered in connection with the accompanying drawings

forming a part hereof, and wherein is disclosed for the purpose of illustration a convenient and satisfactory embodiment of the invention. It is to be noted in this connection that minor changes in the construction 60 and arrangement of parts may be made without departing from the principle of operation of the various parts.

The invention is clearly illustrated in the accompanying drawings, in which:

Figure 1 is a top plan view, the cover of the casing being arranged in an open position and the bristle holders in an extended position;

Fig. 2 is a transverse section of the brush; 70
Fig. 3 is a longitudinal section thereof;

Fig. 4 is a transverse section, the cover of the casing being arranged in a closed position and the brush being folded;

Fig. 5 is a longitudinal section thereof. 75

Fig. 6 is a transverse sectional detail of one of the holders in an extended position.

Fig. 7 is a transverse sectional detail of one of the holders in a folded position.

Fig. 8 is a perspective detail of one of the 80
holders, and

Fig. 9 is a fragmentary longitudinal sectional detail of one of the holders.

Similar characters of reference are employed in all of the above described views, 85 to indicate corresponding parts.

Referring now, more particularly, to the accompanying drawings there is provided a main supporting frame consisting of side pieces 1 and 2, end pieces 3 having their 90 outer ends recessed as at 4 for receiving the curved ends 5 of the side pieces 1 and 2 while carried with the end pieces is a back 5'.

With a view toward providing an improved brush a plurality of bars 6 are employed. These bars are rectangular in cross section and have their respective ends reduced and rounded forming in effect trunnions 7 which are journaled in opposed openings in the end pieces 3. One face of each 100
100 of the bars in proximity to one adjacent edge is provided with a series of longitudinal sockets 8 for receiving tufts of bristles 9.

As intimated, improved means have been provided for actuating the brush means to 105 extend the bristles thereof or move them to a folded inactive position. In reducing this feature of the invention to practice a rod 10 preferably rectangular in cross section is slidably mounted in an opening 11 which is 110

slightly larger than the rod for a purpose that will presently appear. In operably connecting each of the bars 6 to the rod, hinges 12 are provided. One leaf 13 of each hinge 5 is counter sunk in a corresponding recess in the upper surface of the rod 10 and is secured therein by means of a suitable fastening device such as a screw 14 while the other leaf 15 is counter sunk in a suitable recess 10 16 in one side edge of the adjacent bar 6 and is removably secured therein by the screw 14. Each of the bars is so spaced from each other on the rod 10 that they may be folded 15 to assume the position indicated in Fig. 4 when the rod 10 is pushed inwardly.

In order to retain the rod in a closed position a lug 17 is formed on the upper edge of the rod 10 and has one face 18 arranged in a plane at approximately right angles to the upper surface of the bar 10 being directly opposed to the head or knob 19 on the outer end of the rod. This face 18 is designed to engage the upper edge of the opening 11 while the other face 20 of the lug is tapered 25 gradually until it meets the upper edge of the rod 10. A similarly shaped lug 21 is formed integrally with the under or lower edge of the rod 10, the vertical face 22 thereof being positioned so as to engage the lower edge of the opening 11 and the outer face of the side pieces 2 subsequent to the pulling of the rod outwardly so as to hold the bristles in an extended position. It will be observed that the arranging of the bristles 30 35 9 in one edge of each of the bars permits of the sides of the bristles being arranged against the corresponding side faces of the adjacent bars when the bristle holders are in a folded or collapsed position.

40 A cover 24 is connected to one end of the frame and is foldable over the face of the brush when the brush is in a closed position, the cover itself being retained in said closed position by means of a tab 25 one end of 45 which is secured to the cover while the main portion passes around the adjacent end and is secured to the bottom or back of the casting by means of a socket 27 carried by the free end thereof which movably engages a head 26 on the bottom.

50 Pockets 28 and 29 are provided on the inner face of the cover and are adapted to

respectively receive a mirror 30 and a comb 31.

It is believed from the foregoing description that a further detail description of the operation is entirely unnecessary. Likewise it is believed that the advantage of this invention will be readily apparent.

As many changes could be made in the above construction and many apparently widely different embodiments of this invention could be made without departing from the scope thereof, it is intended that all matter contained in the above description or shown in the accompanying drawings shall be interpreted as illustrative and not in a limited sense. It is also to be understood that the language used in the following claim is intended to cover all the generic and specific features of the invention herein described and all statements of the scope of the invention, which, as a matter of language might be said to fall therebetween.

Having thus fully described this invention, what is claimed as new and desired to be secured by Letters-Patent is:—

A device of the character described including a rectangular supporting frame one side of which is provided with an oblong opening, a plurality of bars journaled in the ends of the frame at uniformly spaced intervals, bristles projecting from the outer faces of the bars, a rod slidably mounted in the opening in the frame and of a thickness less than the height of the opening, a plurality of hinges, the leaves of the hinges being respectively attached at uniformly spaced intervals to the rod and to one side edge of the adjacent bar so that when the rod is slid the bars will be rocked, a knob formed on the outer end of the rod for facilitating the operation thereof, and lugs having straight faces and inclined faces formed on the upper and lower edges of the rod for engaging respectively with the inner and outer faces of the said frame adjacent the opening subsequent to the slidable and vertical movement of the rod for holding the bars so that the bristles will be retained either in an operative or inoperative position.

In testimony whereof I affix my signature.

JAMES DE B. WALBACH.
